FIGURE 1 is a side view of a boom embodying my design shown on a tractor, the boom being illustrated in an elevated substantially horizontal position;

FIGURE 2 is a plan view of the boom shown in FIGURE 1;

FIGURE 3 is a front view looking at the boom from the right-hand end of FIGURE 1; and

FIGURE 4 is a rear view looking at the boom from the left-hand end of FIGURE 1.

The bottom of the boom is substantially plain.

The dotted line showing in the drawing is for illustrative purposes only.

I claim:

The design for a boom for loader, substantially as shown and described.
